REGISTER SELECTING MECHANISM FOR
ACCOUNTING MACHINESWalter A. Anderson, Trumbull, Conn., assignor to
Underwood Corporation, New York, N. Y., a
corporation of New York

Application July 25, 1951, Serial No. 238,445

6 Claims. (Cl. 235—60.48)

1

This invention relates to accounting machines having two or more registers and more particularly to an improved mechanism for selecting the said registers for operation, and for printing signals identifying the selected registers.

In accounting practice, it is often desirable to accumulate amounts entered in the machine keyboard in both registers, print totals of one of said registers at the completion of each posting operation, and print a grand total from the other register after completing a series of postings over a predetermined period of time.

It is, accordingly, one of the objects of the present invention to provide a mechanism for automatically selecting one or the other of the registers for operation in certain columnar positions on a work sheet, and for selecting them for operation jointly in other columnar positions thereon.

Another object of the invention is to provide means for manually selecting the registers for operation individually or jointly.

Still another object of the invention is to provide means operable under the control of the manual register selecting means for enabling the printing of signals identifying the register or registers selected thereby.

A further object of the present invention is to provide means for automatically and manually selecting the registers wherein elements common to both means, upon being actuated by either means, selects the registers without interference with, or detriment to the other means.

A still further object of the present invention is to provide a combined automatic and manual register selecting means which is simple in construction, economical to manufacture and assemble, and which is dependable in operation.

With these and incidental objects in view, the invention consists in certain novel features of construction and combinations of parts, the important elements of which are set forth herein in a preferred embodiment hereinafter described with reference to the drawings accompanying and forming part of this description.

In the drawings:

Figure 1 is a right side elevation of the machine showing the parts in normal position,

Figure 2 is a right side elevation showing the manual register selecting slide,

Figure 3 is a left side view showing the register selecting structure in position to select the upper register,

Figure 4 is a plan view showing a part of the register selection mechanism in position to select both the upper and lower registers,

2

Figure 5 is a view similar to Figure 4 but showing the mechanism in position to select the lower register,

Figure 6 is a perspective view showing a part of the register selecting structure.

The invention is herein exemplified in a machine similar in character to the one disclosed in Patents No. 1,946,505 and 1,946,823, to Oscar J. Sundstrand, dated February 13, 1934, and in Patent No. 2,251,100 to W. A. Anderson, dated July 29, 1941, to which reference may be had for an understanding of features not fully illustrated or described herein.

General description

In general, the machine includes, in part, a keyboard comprising amount setting keys, a motor key for controlling operation of the machine by an electric motor, and function controlling keys. Also included in the machine are controls for automatically conditioning the machine for performing its various functions. A traveling paper carriage is provided to carry a cylindrical platen for supporting a work piece and to carry control elements for actuating automatic controls in the various columnar positions of said carriage. The machine includes two registers, each of which is usable to add and subtract, and is provided with means for automatically introducing the fugitive unit which means automatically conditions the machine for the taking of a credit balance or negative total, and type bars operating under the control of the said amount setting keys or the said registers for printing entered amounts and totals of the registers respectively on the work sheet.

Detailed description

Referring to Figure 1 of the drawings, the machine includes a plurality of type bars 24 which carry type 25 and are supported for vertical reciprocatory movement on a bar 22 and a slotted bar 23 for printing on a work piece supported on a cylindrical platen 26 mounted in a traveling paper carriage (not shown). The machine is operated by a motor (not shown) which is suitably connected to a main shaft 30, Figures 1 and 3, carrying an arm 31, to rock the shaft 30 clockwise, from its normal position, as seen in Figure 3, and return it to complete a machine cycle. A link 32 connects the arm 31 and a lever 33 pivoted on the machine frame at 34, and on the other side of the machine a link 35, Figure 1, connects a lever 36, pivoted at 37, on the machine frame to an arm 38 affixed on the main shaft 30. Upon rocking the shaft 30 clockwise, Figure 3, the mem-

bers 33 and 36 are rocked counterclockwise about their pivots 34 and 37 to act upon levers 41 and raise the type bars to their various type printing positions, and upon the return of the main shaft 30 to its normal position, to restore type bars 24 to their normal positions by means of a bar 44, in the manner disclosed in the Patent 1,946,505 referred to.

Each of the numeral type bars 24 carry racks 45 and 47, slidably supported on studs 48 therein, and normally tensioned downwardly by means of springs 49 to enable tens transfers and the introduction of the fugitive one in the conventional manner. A pair of registers 57 and 58 are mounted between said racks 45 and 47 on shafts 53 and 54.

The register wheels are arranged so that the wheels 57 are moved into mesh with the racks 45 for addition and 47 for subtraction, while the wheels 58 are moved into mesh with the racks 47 for addition and 46 for subtraction. The means provided for such movements include, generally, a composite slide member 61, Figure 1, supported on hangers 62 and 63 which are pivoted on the machine frame, slide 61 being moved leftwardly and rightwardly by means of a cam member 59 through a link 60 by means of the pawl 64 secured to arm 38.

Affixed in the composite slide member 61 are studs 66 and 67 on which are slidably supported levers 68 and 69 for shifting the upper and lower register wheels 57 and 58, respectively, into mesh with their associated racks 45 and 47. The levers 68 and 69 are connected by means of a link 70 and are normally urged leftwardly in Figure 1 to hold the register wheels 57 and 58 out of mesh with the racks 45 and 47 by means of a common spring 71, connecting the link 70 and the composite slide member 61. The levers 68 and 69 are each provided with two L-shaped apertures 75, engaging pins 77, in plates 79 and 80 secured to shafts 81 and 82 respectively. Secured to the opposite end of the shafts 81 and 82 are plates 83 and 84, Figure 3, which plates are connected with the register wheel shafts 53 and 54 by means of links 85 and 86. In the drawings the levers 68 and 69 are positioned for engagement with the lower pins 77 to enmesh the register wheels 57 and/or 58 for addition. The levers may be moved to engagement with the upper pins 77 to mesh the register wheels and racks for subtraction and credit balances in the manner disclosed in the above patents. Meshing of the wheels 57 and 58 and the racks 45 and 47 is obtained by either automatically or manually selecting either or both of the levers 68 and 69 for movement by means of the studs 66 and 67, and thereafter moving the composite slide member 61 rightwardly to the position shown in the drawings by means of the cam member 59 and arm 38.

Automatic selection of the upper register

Referring to Figures 1, 4, 5 and 6, the machine is provided with a plurality of control members 90 supported for slidable movement on studs 91 in a control box 91 affixed to the machine frame. A sliding member 92, carrying a pin 93 engaging a slot in the control member 90, is slidably supported for movement laterally on the machine in brackets 95 affixed to the machine frame, and is normally tensioned leftwardly, as seen in Figures 4 and 5, by a spring 96. Mounted loosely on the pivot 34 and extending rearwardly into the path of movement of the sliding member 92 is an arm 98, provided with a rear tongue 99 supported for slidable movement in a bracket 100 firmly secured

to the machine base, said arm 98 being also provided with a formed lug 101. A spring 113 connected between arm 98 and bracket 95 tensions arm 98 into its leftmost position as shown in Figure 6 against the end of slide 92. Arm 98 may be moved rightwardly into two additional positions by a lug 160, Figures 1, 4 and 5, mounted in a plate 161, Figure 1, attached to the traveling carriage. If pin 160 is in line with other pins in the plate 161, particularly the pin used to arrest the carriage in a columnar position, it moves slides 90 and 92 and arm 98 to the rightmost position as shown in Figure 5 but if the pin 160 is offset to the left from the other pins, slides 90 and 92 and arm 98 are moved only to a mid-position as shown in Figure 4. The selection of the registers under control of arm 98 in each of its positions will be described at a later point in this specification.

Referring to Figures 3 and 6, a lever 105 with an ear 106 is pivoted on a shaft 59 and pivoted thereon, on a stud 107, is a dog 108 tensioned to normally bear against the ear 106 by means of a torque spring 110. The stud 107 is provided with two steps for engagement with the member 98 in its two leftmost positions, arm 98 in its right hand position being out of the path of stud 107, see also Figures 4 and 5. The lower arm of lever 105, see Figure 3, is provided with a slot 117 in which loosely rests a pin 118 affixed in a slide 119 supported for vertical movement on the pivot 34, and connected at its lower end to a lever 121. Pivoted on a stud 122 in the lever 105 is a member 123 having a cam edge 124, and an ear 126 normally tensioned to bear against the bottom of pin 118 by means of a spring 127 connected between lever 105 and member 123. Rigid in the lever 33 is a stud 128 arranged to act during a machine cycle upon the dog 108, and a roller 129 arranged to engage the cam edge 124 of the member 123 to position lever 105 and slide 119 during each cycle to determine register selection as will be later described.

Lever 121 is pivoted at 134 on an arm 135 affixed on a shaft 136 pivotally supported in the frame and carries a stud 137 normally tensioned to bear against the lower edge of arm 135 by means of a spring 139 between lever 121 and arm 135 to provide a yielding connection of the parts. The arm 135 is provided with notches on its upper edge in which is engaged a spring urged detent 144 to retain the parts 105, 119, 121 and the register or registers selected in that condition during cycling of the machine.

Affixed to the opposite end of shaft 136, Figure 1, is an arm 150 carrying a stud 151. Pivoted on stud 151 are two arms 152 and 155 each slidably at its upper end on a stud 153 or 156 on the levers 68 and 69 respectively. The forward edge of each arm rests against the studs 66 or 67 respectively in slide 61 and determines that the levers 68 and 69 shall move with slide 61. The forward edges of arms 152 and 155 are, however, notched so as to free the upper lever 68 from stud 66 when arm 150 is in its clockwise position and to free lever 69 from stud 67 when arm 150 is in the counterclockwise position as shown in Figure 1. Thus in these two positions only the lower or upper slides 68 or 69 will be shifted and only one register will be engaged with the racks 46 or 47. In the central position of arm 150, both levers are moved with slide 61 and consequently both registers will be engaged with racks 46 and 47.

Selection of the registers is controlled by the

movement of control member 90 from the normal Figure 6 position to one of the two positions shown in Figures 4 and 5 by means of pins 160 fixed in the control plate 161 supported in the traveling paper carriage (not shown), in rows as above set out. Selection of the upper register wheels 57 only is the normal operation of the machine when no pin 160 is effective. Therefore the parts normally remain in the position illustrated in Figures 1, 3 and 6. Accordingly in any columnar position in which a pin 160 is omitted from the control plate 161, the position of the control member 90 is unaffected so long as the carriage rests in that columnar position, and arm 98 is tensioned to the left toward the Figure 6 position. During an ensuing machine cycle and after slide 61 has disengaged the registers, the stud 128 in the lever 33 strikes the face of dog 108 to rock lever 105 counterclockwise, Figure 3, enabling arm 98 to move in front of the higher stop face of stud 107 if it is not already there, and raising slide 119 and lever 121 to the Figure 3 position. Roller 129 then strikes the cam edge 124 of lever 123 and rocks it clockwise but as member 105 is restrained from moving by means of the engagement of stud 107 with arm 98, such movement of lever 123 is ineffective to return lever 105 clockwise and lever 123 returns to its Figure 3 position when roller 129 moves away from the face 124 of member 123 during the second part of the machine cycle.

Movement of slide 119 to its upper position at such time, determines selection of the upper register during the next part of the machine cycle. Raising of slide 119 through lever 121 and shaft 136 lowers the arm 150, Figure 1, to put the notch in arm 155 in back of stud 67 so that subsequent movement of slide 61 to the rear will not cause register 58 to be engaged with the racks 47 or 48, only the upper register 57 engaging the racks. Detent 144 acts to retain shaft 136 and arms 152 and 155 in their adjusted positions during the latter half of the machine cycle.

Automatic selection of both registers

Should it be desirable to select both sets of register wheels 57 and 58 for simultaneous operation, a pin 160 is inserted in control plate 161 but is offset from the line of the other pins as shown in Figure 4. Such pin 160 when effective moves, through slide 92, arm 98 into the Figure 4 position in alignment with a lower stop face on stud 107. Now during an ensuing machine cycle, stud 128 strikes dog 108 to rock arm 105 to its counterclockwise position as described above. Immediately thereafter roller 129 engages the cam face 124 of lever 123 and rocks the lever 123 clockwise. Lever 105 will follow the motion of lever 123 until stud 107 strikes with its lower stop face on tongue 101 of arm 98 and stops the lever 105.

Slide 119, lever 121, shaft 136 and arms 150, 152 and 155 are thus moved into a central position. In such position, neither arm 152 nor 155 has its notch in alignment with a stud 66 or 67 and hence both levers 68 and 69 follow the subsequent movements of slide 61 to engage both the upper and the lower register wheels 57 and 58 with the racks 46 and 47.

Automatic selection of the lower register only

When it is desired to select only the lower register 58 for any columnar position on a work sheet, pin 160 for that column is placed in line with the other pins for that column in plate 161.

Such a pin when it engages slide 90 moves the slides 90 and 92 and arm 98 to their extreme right hand position as shown in Figure 5. When arm 98 is in such position it is clear of stud 107 and hence when lever 105 is urged clockwise by roller 129 acting through lever 123, there is nothing to stop arm 105 until it reaches its clockwise limit. This movement of lever 105 depresses slide 119 to rock shaft 136 and raise arms 150, 152 and 154 to their upper positions. In such position, the engaging mechanism for register 57 is ineffective since the notch in arm 152 is aligned with stud 66 and only the register 58 will be engaged during the remainder of the machine cycle.

It should be noted that stud 128 on its return stroke rocks dog 108 idly about its pivot stud 107 and hence does not alter the position of slide 119 and lever 105. It should also be noted that lever 105 is restored to its counterclockwise position near the start of each cycle and arm 98 at this time is free to be moved to the left into a new position if such is required by the automatic carriage controls.

25

Manual selection of the registers

In accounting practice, it is frequently desirable to make a manual selection of the registers. In the interests of economy of manufacture, ease of assembly and dependability of operation, the present invention provides a single train of mechanism for automatically or manually selecting the registers. For such manual selection, a register selection slide 167, Figure 2, is slidably supported on studs 166 and has a slot 168 embracing a pin 169 fixed in a leg of a cradle 171 pivoted on a stationary shaft 172. Pivoted on a stud 174, Figure 1, in a second leg of the cradle 171 is a link 176 connected by a stud 180 to a member 181. The member 181 is fixed to a member 182 and both of these members are pivotally supported on a stud shaft 183. A link 184, pivoted on the member 182, is connected to an arm 186, Figure 6, secured to an upstanding shaft 187 journaled in the machine base. Mounted on the shaft 187 is a selector 188 engaging a pin 190 in a lever 191, pivoted on a stud 192 and forming part of the credit balance control mechanism as shown in the above patents. Pivoted on a screw 195 on the machine frame is a lever 197 bifurcated to embrace the pin 190 in the lever 191, and extending upwardly to bear against a pin 199, in the sliding member 92. A spring 200 between lever 197 and slide 92 serves to hold the lever 197 against stud 199.

The register selector slide 167 is arranged for movement to three positions corresponding to the three carriage controlled register selections. Accordingly, with the slide 167 in its extreme forward position, the parts are in the positions shown in Figure 1 in which position the stop portion 101 of the member 98 is aligned with the higher stop face of stud 107, to condition the machine for normally selecting the upper register wheels 57 for engagement with the racks 46 or 47.

Upon movement of the totalizer selector slide 167 to its central position, the cradle 171 is rocked by means of the pin 169, moving the link 176 rearwardly. With this movement of the link 176, the members 181 and 182 are rocked about their common pivot 183, whereupon the link 184, through the arm 186 rotates the shaft 187, Figure 6, in the machine base, and the selector 188, acting upon the pin 190, rocks the member 191 about its pivot 192. The bifurcated lever 197,

engaging the pin 190, is thereby rocked about its pivot 195, whereupon its upper arm, bearing against the pin 199, moves the member 92 rightwardly, to position the stop portion 101 of the member 98 in alignment with the lower stop of the stud 107, and to thereby control engagement of both the upper and lower register wheels 51 and 58 with the racks 46 and 47 for addition or subtraction during cycling of the machine in the same manner as previously described for the automatic selection of the registers.

Likewise, movement of the register selector slide 167 to its rearward position rocks the cradle 171 to its rearmost position, moving the member 176 rearwardly and the slide 92 rightwardly to position the stop portion 101 of the member 98 clear of the stud 107, and thus to condition the machine for selection of the lower register wheels 58 only for addition, subtraction or totaling in the manner previously described.

A detent arm 207 provided with notches is mounted on a bracket 209 on the machine frame and is tensioned downwardly by a spring 212 to engage a pin 211 on the link 176 in one of the notches and thus hold link 176 in any set position.

Manual signal control

In machines of the class described, it is customary to print symbols adjacent the printed amounts to indicate the operation performed during that cycle. In the present machine it is desirable to print such symbols only when the slide 167 is set to alter the normal machine condition. A symbol type bar hammer 234 similar to the other type bar hammers is driven by a spring 236 to print from the associated symbol type bar 24 but is normally restrained by a latch 240 hooking over a tail on the hammer. This latch is released by an arm 242 pivoted on a printing release bar 243, bar 243 moving arm 242 rearwardly about the middle of each cycle. Arm 242 is normally held by a spring 264 in a position clear of latch 240 to prevent symbol printing.

However, if slide 167 is moved into either its central or rearmost position, right in Figure 2, the symbol type hammer release arm 242 is thereby rendered active to enable symbol printing. As seen in Figure 1, stud 174 in cradle 171 will, as the cradle 171 is swung clockwise, cam upwardly the end 253 of an arm of a lever 248. The rear arm of this lever 248 rests on a projection of the latch release arm 242 and swings upwardly the rear end of the arm 242 into engagement with latch 240 whenever slide 167 is in either its central or rear position thus enabling symbol printing when the normal register selection is altered.

The symbol type hammer is also released by depression of the subtraction key to print the subtraction symbol. The subtraction key 221, Figure 2, has a stud 274 thereon, the stud 274, see also Figure 1, normally positioned above an arm 273 pivoted on shaft 275 and resting on an ear 276 of lever 248 to rock lever 248 upon depression of the subtraction key 221. The symbol type bar 24 is adjusted to present the proper symbol to the platen 26 by mechanism forming no part of this invention and substantially as shown in the above patents.

The machine is also provided with an interlock to prevent shifting of slide 167 to a new position during a machine cycle. As shown in Figure 2, the motor bar 283 operates through a spring

284 to depress a slide 285. This slide 285 is connected to a cycle trip wire to initiate a machine cycle in the usual manner and also to rock a cradle 292 pivoted on a shaft 293. The cradle has a lateral ear which is engageable with two ears 296 on link 176 which it will be remembered is directly connected to slide 167. Such engagement will prevent a change in position of slide 167 during a machine cycle or alternately will prevent initiation of a machine cycle if the slide 167 is between two of its positions. The subtraction key 221, Figure 2, has a lower extension 287 engageable with a stud 289 on motor bar 283 to depress the motor bar with the subtraction key and so latch link 176 during subtraction cycles.

A further feature is a provision to prevent a total-taking operation of the machine while lever 167 is in a position to select both registers. As shown in Figure 1, in the central position of slide 167, stud 174 of cradle 171 depresses an arm of a lever 300 pivoted on shaft 255. The lower arm of lever 300 is connected to a pair of spring connected links which extend to the rear and in front of a hinge plate 312. This hinge plate is standard in this type of machine and is moved forwardly by power in a blank cycle to prepare for a total taking cycle. So long, however, as slide 167 is in its central position, links 305 and 306 maintain a pressure on plate 312 and thereby restore it to its rearward position as soon as the plate is released from its power setting means, thus preventing taking of a total on the next machine cycle.

The above description is of a preferred embodiment of my invention and is not to be taken in a limiting sense as many variations in structure are possible without changing the mode of operation of the structure, all coming within the scope of the appended claims.

What is claimed is:

1. In an accounting machine of the class described, having a plurality of registers, register actuators, a cyclically operated means for engaging said registers with and disengaging them from said actuators, a register selection control member and a control plate shiftable relatively thereto for variably positioning said control member, the combination of means individual to each said register for connecting said registers with said engaging means, variably positionable means common to all said registers for variously disabling said connecting means, a power operated member, mechanism operated thereby to invariably move said positionable means to one position, a resilient mechanism connected to said operated mechanism and driven by said power operated member to move said operated mechanism in the opposite direction and an arresting member positioned by said register selection control member to variably arrest movement of said operated mechanism in the return direction thereby effecting a selection among said plurality of registers.

2. In an accounting machine of the class described, having a plurality of registers, register actuators, a cyclically operated means for engaging said registers with and disengaging them from said actuators, a register selection control member and a control plate shiftable relatively thereto for variably positioning said control member, the combination of means individual to each said register for connecting said registers with said engaging means, variably positionable means common to all said registers for variously

disabling said connecting means, a power operated member, mechanism operated thereby to invariably move said positionable means to one position, a resilient mechanism connected to said operated mechanism and driven by said power operated member to move said operated mechanism in the opposite direction, an arresting member positioned by said register selection control member to variably arrest movement of said operated mechanism in the return direction thereby effecting a selection among said plurality of registers, a manually adjustable member, and a connection from said member to said control member to enable manual selection of said registers.

3. In an accounting machine of the class described, having a plurality of registers, register actuators, a cyclically operated means for engaging said registers with and disengaging them from said actuators, a register selection control member and a control plate shiftable relatively thereto for variably positioning said control member, the combination of means individual to each said register for connecting said registers with said engaging means, variably positionable means common to all said registers for variously disabling said connecting means, a power operated member, mechanism operated thereby to invariably move said positionable means to one position, a resilient mechanism connected to said operated mechanism and driven by said power operated member to move said operated mechanism in the opposite direction, an arresting member positioned by said register selection control member to variably arrest movement of said operated mechanism in the return direction thereby effecting a selection among said plurality of registers, a manually adjustable member, a connection from said member to said control member to enable manual selection of said registers, a normally ineffective symbol printing mechanism, and means operated by said manually adjustable member in predetermining positions to enable said printing mechanism.

4. In an accounting machine of the class described having a plurality of registers, register actuators, a power operated member common to all said registers for engaging and disengaging said registers and said actuators, and individual linkages between said power operated member and said registers, the combination of an arm for each linkage to enable or disable said linkage, a member connected to all of said arms and variably positionable to position said arms and thereby select various combinations of said registers for engagement with said actuators by said power operated member, a lever connected to said member, cyclically operated means to invariably restore said lever and said member to one position and thereafter resiliently drive said lever and said member in the opposite direction, an arm variably positionable to variably arrest

return movement of said lever in the opposite direction, a function control member to position said arm, and a member settable in columnar positions to adjust said function control member.

5. In an accounting machine of the class described having a plurality of registers, register actuators, a power operated member common to all said registers for engaging and disengaging said registers and said actuators, and individual linkages between said power operated member and said registers, the combination of an arm for each linkage to enable or disable said linkage, a member connected to all of said arms and variably positionable to select various combinations of said registers for engagement with said actuators by said power operated member, a lever connected to said member, cyclically operated means to invariably restore said lever and said member to one position and thereafter resiliently drive said lever and said member in the opposite direction, an arm variably positionable to variably arrest return movement of said lever in the opposite direction, a function control member to position said arm, a manually positionable slide, and a lever moved thereby to shift said function control member into various register selecting positions.
6. In an accounting machine of the class described having a plurality of registers, register actuators, individual register engaging means, and a cyclically operating slide common to said engaging means for engaging and disengaging selected registers with said actuators, the combination of an arm for each register, said arm positionable to connect said individual register engaging means with said common slide, a member common to all said arms and operable to various positions to selectively render certain of said arms effective to connect the associated register engaging means and said slide, a member cyclically operated in one direction to an invariable position and resiliently restored in the opposite direction to selectively position said member common to said arms, a stop member positionable to arrest restoration of said cyclically operating member, and a function control member to set said stop member in different arresting positions, a shiftable plate positionable in different columns, a manually shiftable key and individual connections from said plate and said key to variably position said function control member.

WALTER A. ANDERSON.
